GUTTER FOR BOWLING ALLEY

Melvin Blatt, 1610 Westover Road, Morrisville, Pa.

Filed July 14, 1958, Ser. No. 748,235

7 Claims. (Cl. 273—51)

This invention relates to bowling alleys and is directed particularly to improved gutter constructions to be located at opposite sides of the alley to receive bowling balls which roll off the side of the playing surface.

The gutters heretofore used in bowling alleys generally have been formed of plywood members of concave form which are made in sections and supported at spaced points throughout the length thereof by means of saddles or supporting blocks conforming to the lower surface of the gutter. The edge of such plywood gutters at the side thereof adjacent the alley is usually secured in place by nailing through the plywood to the edge board of the alley. The opposite edge of the gutter is then secured in place by a cap strip which serves to hold the gutter down against the supporting saddles. The cap strip is secured to the division boards between adjacent alleys or to members overlying the ball return channel.

In view of the care and accuracy required in constructing bowling alleys, the operations necessary to install a plywood gutter properly requires skilled workmen and a considerable amount of time. Moreover, even when every precaution is taken, one or more of the nails securing the gutter to the edge board of the alley may be loosened by the frequent shocks or impacts of the bowling balls falling into or traveling along the gutter, or by reason of dampness which tends to warp the plywood.

Furthermore, the end of the gutter adjacent the foul line of the alley is usually closed by means of an inclined or wedge shaped block which must be fitted carefully against the concave plywood gutter member. This operation not only requires further time and care on the part of skilled workmen, but always leaves a joint or seam at the end of the gutter in which dirt tends to accumulate.

In accordance with the present invention, these and other objections to the gutter constructions heretofore employed in bowling alleys are overcome and improved gutter elements are provided which are simple and economical to produce and install.

These advantages are preferably attained by providing the gutter members with a longitudinally extending flange or retaining means adapted to fit into a groove or other recess in the edge board of the alley so as to hold the gutter in place without the use of nails, screws or other fastening means. The flange and groove thus provided permit quick, easy assembly of the gutter member with respect to the alley and further affords support for the gutter member throughout the length thereof.

In accordance with the present invention, it is also possible to construct the gutter members so that they extend across the division board or structure between two alleys and have portions of the gutters of adjacent alleys embodied in a single piece. Such constructions have the further advantage of increased ease of installation and inherent retention of the element in place. If desired, such a gutter element may also embody a portion of the track for returning the bowling ball or may have such a track mounted thereon.

In the preferred form of the invention, the gutter

2

members are formed of molded plastic material and may be fabricated so as to have an integral inclined end portion, for location near the foul line which presents a seamless, smooth surface facilitating cleaning of the gutter.

Accordingly, the principal object of the invention is to provide a novel type of gutter construction for bowling alleys which is simple and economical to produce and install.

Another object of the invention is to provide a gutter element for bowling alleys which is formed of molded plastic material.

A further object of the invention is to provide gutter elements which present a seamless inclined end surface which facilitates cleaning of the gutter.

An additional object of the invention is to provide constructions which embody portions of the gutters for two adjacent bowling alleys.

These and other objects and features of the present invention will appear from the following description thereof of wherein reference is made to typical embodiments of the invention for the purpose of indicating the nature thereof but without intending to limit the scope of the invention thereby.

25 In the drawings:

Fig. 1 is a transverse sectional view through a typical form of gutter element embodying the present invention;

Fig. 2 is a longitudinal sectional view of a portion of an end member employed in the construction of a 30 gutter embodying the present invention;

Fig. 3 is a transverse sectional view through an alternative construction embodying the present invention; and

Fig. 4 is a view similar to Fig. 3 showing a further 35 alternative form of the present invention.

In that form of the invention chosen for purposes of illustration in Figs. 1 and 2, the bowling alley has a playing surface 2 with an edge board 4 formed with a groove or recess 6 which extends lengthwise of the edge board 40 below the playing surface 2 of the alley. The gutter element is indicated generally at 8 and may be formed of any suitable material. In the preferred construction, the element 8 is a molded body of plastic material reinforced with glass fiber fabric or other fibrous or textile-like material. However, the gutter element can be formed of extruded molded or stamped plastic, metal or other material or may be fabricated from plywood or other members and in any other preferred manner to provide the desired cross-sectional shape to the element.

50 As shown, the element 8 is provided with a concave, upwardly facing ball receiving channel 10 and is provided at the side thereof adjacent the playing surface of the alley with a downwardly extending leg 12. The leg 12 is preferably inclined inwardly at a slight angle beneath the channel 10 and is formed at its lower edge with an outwardly extending flange 14 of such size that it will fit within the longitudinal groove 6 in the edge board 4 of the alley.

The groove 6 may be positioned as shown in Fig. 1 adjacent the lower edge of the edge board 4 so that the lower surface of flange 14 rests directly upon the upper face of the foundation of sheet material 16 or other surface upon which the boards 18 forming the playing surface of the alley are positioned. In any event, whether groove 6 is in the lower position shown in Fig. 1 or is spaced above the foundation sheet, the flange 14 may be readily inserted in the groove 6 and will be securely and accurately positioned and held in place without the use 65 of any nails, screws or other fastening means. If desired, the flange 14 may further be formed with an enlarged bead 15 adapted to be received within a corre-

spondingly enlarged portion of the recess 6 to aid in retaining the flange 14 in place.

The opposite edge portion 20 of the gutter element is preferably also provided with an outwardly extending flange 22 positioned to rest upon the upper surface of the division board 24 between adjacent alleys. A cap strip 26 may then be secured to the division board over the flange 22 by means of screws 28 or other fastening means.

The construction thus provided can be made of reinforced plastic or other material and may be placed and secured in position without driving any nails or fastening means into the edge board 4 of the alley. When the gutter element 8 is formed of reinforced plastic material, it is sufficiently flexible in a transverse direction to permit it to be placed under stress as it is forced into position whereby the leg 12 and flange 14 are continually urged outwardly to retain the flange 14 in the groove 6 in the edge board 4 of the alley. The operation of installing the gutter elements can thus be accomplished quickly and easily in a manner to assure a neat, accurate assembly while a substantial saving in construction costs is effected. Moreover, the edge of the gutter adjacent the playing surface is always held in place and there is no possibility of loosening or the exposure of nails or rough elements to engage the bowling balls even though the gutter is subjected to severe usage.

As shown in Fig. 2, the gutter element 8 may be supported at various points throughout the length thereof by saddles or supporting blocks 30. However, because of the continuous longitudinal support of the gutter element by the leg 12 and flange 22, the saddles 30 may be spaced apart a greater distance than when using a conventional plywood construction. Furthermore, the elements may be readily removed for replacement, if necessary, without extracting nails or otherwise weakening or damaging the edge board of the alley.

Further as shown in Fig. 2, the gutter element located at the end of the gutter adjacent the foul line is provided with an upwardly inclined surface 32 which is formed integral with the concave portion of the gutter. The edges of surface 32 present a smooth rounded corner surface 34 which merges into the concave surface of the channel 10. In this way, the end of the gutter is given an attractive sweeping contour which has no corners or crevices in which dust and dirt may accumulate and cleaning of the gutter is greatly facilitated.

The gutter elements of the present invention may be made up in any desired length. The end gutter element 8 shown in Fig. 2 is, of course, the only element which is formed with the inclined surface 32. The remaining gutter elements, such as that indicated at 8A in Fig. 2 are concave in cross-section throughout the length thereof and may be joined to the section 8 and to other sections by means of cross straps or other connecting members 36 positioned adjacent the abutting ends of the gutter elements. If desired, the gutter elements may have recesses 38 molded in the end portions thereof to receive the connecting members or the connecting members may be embedded in the plastic material in molding the same so that they will be fixedly and permanently attached to the gutter elements in a manner to further simplify the assembly and installation of the gutter.

The gutter construction thus provided may be applied to any desired form of alley installation and may be applied to existing alleys by replacement or modification of the edge boards of the alleys.

In the alternative form of the invention shown in Fig. 3, the construction embodies two gutter sections which are formed in a single piece for use on adjacent alleys. For this purpose the section 40 is formed with a central web 42 which extends across the division board 44 and is provided with gutter portions 46 at the opposite edges thereof. The outer edges of the gutter portions are each formed with a downwardly turned leg 48 and an outwardly projecting marginal flange 50. The flanges 50 are

formed to extend into grooves 52 in the edge boards 54 of adjacent alleys.

The construction thus provided serves to incorporate portions of the gutters for two alleys in a single piece. Moreover, the element is sufficiently flexible transversely so that the legs 48 at opposite sides of the piece may be pressed inward to insert the flanges 50 in the grooves 52 and will thereafter spring outwardly because of the inherent stiffness or resiliency of the material so that both flanges 50 are urged outwardly and serve to retain the element in place.

Such a double gutter construction does not require any fastening means whatever to hold it in place. However, in most installations some form of fastening means such as the screws 55 are employed and are passed through the web 42 into elements of the division structure 44.

In the construction shown in Fig. 4, the web 56 of the element 58 is of sufficient width to extend across the structure 60 between two alleys. The upper surface of web 56 is provided with means forming a part of the ball return track. For this purpose metal or fiber strips 62 are arranged in parallel relation on the web 56 and may be received in grooves 64. The strips 62 on one element are aligned with similar strips in other elements placed in end to end relation to complete the ball return track. The strips 62, of course, may be secured to the web 56 by any suitable means or they may be molded integral with the web if desired.

Further, as shown in Fig. 4, the flanges 14A which engage the edge boards of the playing surface and the recesses into which the flanges extend may be inclined or sloped in form to facilitate application of the gutter element. Such inclined formation also aids in urging the gutter element downward against the foundation sheet 16 by reason of the outwardly urged inclined shape of the flanges 14A.

Gutters for bowling alleys embodying the present invention are easily produced and may be installed very quickly and with a minimum of labor. Moreover, they can be removed, if desired, without damage to the alley. The construction also lends itself to application to existing alleys and when the elements are formed of molded plastic material, the problems heretofore encountered due to dampness and warping are overcome.

The form, length and styling of gutter elements embodying the present invention can obviously be varied to meet any particular needs. The location of the flanges and grooves which secure the edges of the gutter elements in place can also be varied as desired. In view thereof, it should be understood that the particular forms of the invention shown in the drawing and described above are intended to be illustrative only and are not intended to limit the scope of the invention.

I claim:

1. A bowling alley comprising a playing surface having an edge board with a longitudinally extending recess in the laterally facing surface thereof and an elongated gutter element positioned adjacent said edge board and having a concave upwardly facing ball receiving channel therein, the edge of the gutter element adjacent the edge board having an outwardly projecting flange thereon positioned in the recess in the edge board, the opposite edge of the gutter element being fixedly secured in place and said gutter element being transversely flexible and resilient whereby the inherent resiliency thereof serves continuously to urge said flange into said recess.

2. A bowling alley comprising a playing surface having an edge board with a longitudinally extending recess in the laterally facing surface thereof, and a gutter element formed of molded plastic material presenting a concave upwardly facing surface and provided with a flange extending along one edge thereof positioned in said recess in the edge board, said gutter element being transversely yieldable and resilient and said flange being

continuously urged into said recess by the inherent resiliency of the gutter element.

3. A gutter for a bowling alley comprising a channel member which is transversely yieldable and has a supporting leg extending downward along an edge thereof and terminating in an outwardly projecting flange for engagement with an edge board of a bowling alley.

4. A pair of gutters for adjacent bowling alleys comprising a unitary piece of material formed with a central web shaped to extend across a division structure between adjacent alleys and having parallel channel shaped gutter forming portions located at opposite sides of said web and arranged in parallel relation, said gutter forming portions having outwardly extending flanges on the outer edges thereof engageable with the edge boards of adjacent alleys, said material being transversely yieldable and normally tending to assume a position urging said flanges apart.

5. A bowling alley having a playing surface embodying longitudinally extending wooden members including an edge board located at the side of said playing surface, said edge board presenting a laterally facing surface provided with a longitudinally extending groove spaced downwardly from said playing surface, a gutter member extending lengthwise of the alley adjacent said edge board and presenting an upwardly facing concave surface, the side of said gutter member adjacent said edge board having a downwardly extending leg positioned adjacent the laterally facing surface of said edge board, a longitudinally extending flange on said leg extending into the

5

groove in the edge board and means adjacent the opposite side of the gutter member cooperating with said flange to hold the gutter member in place with respect to said playing surface.

6. A bowling alley of the character defined in claim 5 wherein said gutter member is transversely yieldable and resilient and said flange is continuously urged into said groove by the inherent resiliency thereof.

7. A bowling alley comprising a supporting structure 10 presenting an upwardly facing surface, means forming a playing surface resting upon the upwardly facing surface of said structure and including an edge board extending lengthwise of the alley at one side of the playing surface, said edge board having a laterally facing surface with a groove therein extending longitudinally of the edge board adjacent the upwardly facing surface of the supporting structure, a gutter member positioned adjacent said edge board and presenting a concave ball receiving channel, a downwardly extending leg on the gutter member positioned adjacent the laterally facing surface of said edge board and having an outwardly extending flange thereon resting upon the upwardly facing surface of the supporting structure and extending into said groove.

15

20

25

30

groove in the edge board and means adjacent the opposite side of the gutter member cooperating with said flange to hold the gutter member in place with respect to said playing surface.

6. A bowling alley of the character defined in claim 5 wherein said gutter member is transversely yieldable and resilient and said flange is continuously urged into said groove by the inherent resiliency thereof.

7. A bowling alley comprising a supporting structure 10 presenting an upwardly facing surface, means forming a playing surface resting upon the upwardly facing surface of said structure and including an edge board extending lengthwise of the alley at one side of the playing surface, said edge board having a laterally facing surface with a groove therein extending longitudinally of the edge board adjacent the upwardly facing surface of the supporting structure, a gutter member positioned adjacent said edge board and presenting a concave ball receiving channel, a downwardly extending leg on the gutter member positioned adjacent the laterally facing surface of said edge board and having an outwardly extending flange thereon resting upon the upwardly facing surface of the supporting structure and extending into said groove.
